UNITED STATES PATENT OFFICE

2,292,262

WATER GATE

John Winston Alter, Salt Lake City, Utah

Application January 15, 1941, Serial No. 374,575

11 Claims. (Cl. 61—25)

This arrangement relates to gates and more particularly to a gate for an irrigation canal or other fluid or material conveying duct.

An object of this invention is to provide a gate including a means for supporting the gate in a canal, duct or the like which is so constructed as to permit a predetermined amount of water to pass therethrough.

Another object of this invention is to provide a gate of this type which embodies a self-cleaning means so that after the gate has been in an open position for a period of time, it may be closed and any fibrous or flexible material or other undesirable debris which may cling thereto will be removed during the movement of the gate to a closed position.

A further object of this invention is to provide a gate of this kind which can be economically manufactured and installed and which in operation is more satisfactory than any device now in use or available.

A still further object of this invention is to provide a gate of this kind which is provided with means for locking the gate in a selected open position so as to permit a predetermined quantity of water to pass therethrough.

To the foregoing objects and to others which may hereinafter appear, the invention consists of the novel construction, combination and arrangement of parts as will be more specifically referred to and illustrated in the accompanying drawing wherein are shown embodiments of the invention, but it is to be understood that changes, variations and modifications may be resorted to which fall within the scope of the invention as claimed.

In the drawing:

Figure 1 is a detail front elevation of a gate structure constructed according to an embodiment of this invention showing the gate in closed position.

Figure 2 is a detail end elevation of the gate structure.

Figure 3 is a sectional view taken on the line 3—3 of Figure 1.

Figure 4 is a fragmentary sectional view taken on the line 4—4 of Figure 1.

Figure 5 is a fragmentary sectional view taken on the line 5—5 of Figure 1.

Figure 6 is a fragmentary sectional view taken on the line 6—6 of Figure 1.

Figure 7 is a fragmentary front elevation of the cleaning end of the gate.

Referring to the drawing, the numeral 10 designates generally a frame structure which is

adapted to be mounted in a canal, ditch, duct or the like through which fluid or other material is adapted to pass. The frame structure 10 is formed of angle iron and comprises a base angle bar 11 having one side 12 thereof horizontal and the other side 13 thereof vertical. A vertically disposed angle bar 14 is formed integral with the angle member 11 and has the lower end of the inner side 15 thereof cut off on an angle as at 16 so that the outer web or side 18 may be bent at a right angle and the mitered or angled portion 16 disposed in contacting relation with a mitered or angled portion 17 of the web or side 13.

15 The vertical side frame member 14 has formed integral therewith a substantially semi-circular frame member 19 which has an inner side 21 extending upwardly from the inner side 15 of the angle member 14 and an outer side 22 extending from the right angular outer side 18 of the angle member 14. The opposite end of the arcuate or semi-circular frame member 19 is extended downwardly as at 23, the extension 23 being parallel with the vertical angle member 14.

20 The extension 23 is formed with an inner side 24 integral with the inner side 21 and an outer side 25, which is integral with the outer side member 22.

25

The lower end of the extension 23 is connected 30 to the base angle member 11 by forming an extension 26 with the outer side member 12 of the angle member 11 and bending this extension upwardly at right angles. The right angular extension 26 is secured by fastening devices 27 to 35 the inner side of the outer side or web 25 as shown in Figure 1.

A plate 28 is disposed within the rectangular area of the frame structure formed by the base angle member 11 and the vertical side members 40 14 and 23. The plate 28 is adapted to be secured to the inner sides 13, 15 and 24 of the angle members 11, 14 and 23, respectively, by fastening devices 29. The fastening device 29 and fastening devices 27 may be in the form of 45 rivets or the like. The plate 28 is formed with an arcuate cut-out 30 which is substantially semi-circular in front elevation and which extends downwardly from the arcuate frame member 19. The radii of the arcuate cut-out 30 are substantially shorter in length than the radii of the semi-circular frame member 19. A semi-circular gate or closure 31 is adapted to slidably engage at its outer convex edge in the cut-out 30 and the gate 31 is pivotally supported within the cut-out 30 from a pivot member 32. The pivot mem-

ber 32 is extended through a vertical side 33 of a horizontally disposed angle member 34, the pivot member 32 being in the form of a rivet or the like and preferably a washer 35 is interposed between the vertical side 33 of the angle member 34 and the adjacent face of the gate 31.

The angle member 34 is formed with a horizontal side 36 which is extended at right angles at the opposite ends of the vertical side 33 as at 37 and 38 and these extensions 37 and 38 are secured by fastening devices 39 and 40, respectively, to the outer side members 18 and 25, respectively. The opposite ends of the vertical side 33 of the angle member 34 are adapted to overlap and engage against the inner sides 15 and 24 of the angle members 14 and 23 as shown in Figure 3.

An angle-shaped handle 41 is secured by suitable fastening devices 42 to the face of the gate or closure 31 opposite from the horizontal upper frame member 34. The handle 41 extends beyond the vertical side frame member 14 as shown in Figure 1 and has a vertical side 43 disposed flat against the adjacent vertical side of the closure 31 and also has a horizontal side 44 extending laterally from the closure 31 and oppositely from the horizontal side 36 of the upper frame bar 34.

The closure or gate 31 has secured to the opposite faces thereof adjacent the arcuate edge, a pair of arcuate strips 45 which are secured to the gate or closure 31 by fastening devices 46. The arcuate strips 45 extend beyond the arcuate edge of the closure 31 and overlap the convex edge portion of the stationary plate 28 so as to form therebetween a groove 47 within which the stationary plate 28 engages. The arcuate strips 45 form a means whereby the fluid such as water or the like is adapted to be prevented from passing between the gate or closure 31 and the cut-out 30 of the stationary plate 28. The strips 45 therefore form with the arcuate or convex edge 30 a tongue and groove sealing connection between the closure 31 and the stationary plate 28.

In order to provide a means whereby the gate or closure 31 may be held in a selected open position, I have provided a plurality of spaced apart holes or openings 48 in the inner side 21 of the frame member 19. The handle member 41 has fixed thereto as by fastening devices 49, an angle member 50 in the form of a keeper or the like which has an opening 51 therethrough. The opening 51 is adapted to be moved into registry with a selected opening 48 and a lock or pin may then engage through the registering openings 48 and 51 so as to lock the gate 31 in the desired open position. The semi-circular frame member 19 on the inner side 21 thereof is provided with a plurality of circumferentially spaced apart lugs or plates 52 which are secured to the inner side member 21 by fastening devices 53. The lugs or plates 52 project inwardly from the inner concave edge of the inner side member 21 and are adapted when the gate 31 is moved to a partly or completely open position to slidably receive the arcuate strips 45 of the gate 31.

The strips 45 at the ends thereof opposite from the handle member 41 are formed with cleaning blades 54 which are adapted to clean the fibrous or flexible material or articles which engage over the convex edge of the plate 28. The cleaning operation is effected when the gate 31 is moved to a closed position.

The cleaning members 54 are formed integral with the strips 45 and are formed in substantially

V-shape in side elevation so that the fibrous or flexible material which engages over the concave edge 30 of the plate 28 may be readily cut off or removed from the concave edge 30 during the movement of the gate 31 to a closed position.

In the use and operation of this gate structure, the frame 10 is adapted to be fixedly secured in a canal, ditch or other duct. Preferably, the depth of the canal or ditch is substantially equal to the length of the parallel vertical side members 14 and 23. When it is desired to either partly or completely open the gate 31, the handle 41 is swung in a counter-clockwise direction as viewed in Figure 1 and if the gate 31 is thereby completely opened, the handle 41 is moved to a diametrically opposite position from that shown in Figure 1. In this completely open position, the gate member 31 will have the arcuate strips 45 thereof engaging on opposite faces of all of the guiding lugs or plates 52. A padlock or pin may be extended through the registering openings 51 and 48 so as to hold the gate 31 in its completely opened position. By providing the keeper 50 with the spaced apart openings 48, the position of the gate 31 cannot be tampered with. If it is desired to only open the gate 31 part-way, the handle 41 is raised to the desired position and then locked by extending the bolt of the padlock or a pin through the selected opening 48 which registers with the opening 51 of the keeper 50.

During the movement of the gate 31 to a closed position, the cleaning blades or members 54 will clean the overlapping material which engages over the arcuate edge 30 of the plate 28. Preferably, the upper edge of the gate 31 is cut out in V-shape as at 55 so as to provide proper clearance for the back sides of the blades 54 and so that the gate 31 may assist in cleaning the arcuate edge of the plate 28. Assuming that the gate 31 is moved to only a half open position and that the level of the water or fluid does not exceed the height of the bar 34, the fluid is adapted to pass through the sector formed between the upper edge of the gate 31 from the pivot 32 and the lower edge of the vertical side 33 of the frame bar 34. By opening the gate in this manner, it will be possible to more accurately determine the amount of fluid which is being delivered from one side of the gate to the other side than would be the case if the gate 31 were opened from the bottom thereof as in the conventional type of gate.

This gate structure in the present instance is made out of flat sheet metal and angle iron and in the event the seal formed by the arcuate groove forming members 45 is not sufficient to prevent leakage of liquids from one side of the gate to the other, there may be provided additional groove forming members 45 and additional plates 28. It will also be understood that if desired suitable arcuate gaskets or the like may be interposed between the confronting faces of the strips 45 and the stationary plate member 28.

A gate structure has been constructed according to this invention and placed in actual operation and use, and has been found more efficient than gates at present available. While the gate structure herein shown has been made out of metal, it may also be made out of wood or other material.

This gate structure has been designed for manual operation by lifting the handle 41, but it will be understood that if desired, other means may be provided for shifting the position of the

gate 31 where this gate is made too large for easy manual movement.

What I claim is:

1. A water gate structure comprising a vertically disposed rectangular frame formed of angle bars, a plate secured to said frame and having a semi-circular cutout extending downwardly from the upper edge thereof, a semi-circular frame bar extending upwardly from said rectangular frame, a semi-circular gate engageable within said cutout, means pivotally supporting said gate for rotary movement relative to said cutout, means for rotating said gate, a pair of arcuate strips fixed to said gate and overlapping the marginal edge of said cutout, and guide means carried by said semi-circular bar and engageable between said strips when said gate is raised to an open position.

2. A water gate structure comprising a vertically disposed rectangular frame formed of angle bars, a plate secured to said frame and having a semi-circular cutout extending downwardly from the upper edge thereof, a semi-circular frame bar extending upwardly from said rectangular frame, a semi-circular gate engageable without said cutout, means pivotally supporting said gate for rotary movement relative to said cutout, means for rotating said gate, a pair of arcuate strips fixed to said gate and overlapping the marginal edge of said cutout, guide means carried by said semi-circular bar and engageable between said strips when said gate is raised to an open position, and a keeper carried by said rotating means, said semi-circular bar having openings therein adapted for registration with said keeper whereby a gate locking means may be inserted through said keeper and a selected opening for locking said gate in a selected position.

3. A water gate structure comprising a vertically disposed rectangular frame formed of angle bars, a plate secured to said frame and having a semi-circular cutout extending downwardly from the upper edge thereof, a semi-circular frame bar extending upwardly from said rectangular frame, a semi-circular gate engageable within said cutout, means pivotally supporting said gate for rotary movement relative to said cutout, means for rotating said gate, a pair of arcuate strips fixed to said gate and overlapping the marginal edge of said cutout, guide means carried by said semi-circular bar and engageable between said strips when said gate is raised to an open position, and a cutter at one end of each strip adapted upon movement of said gate from an open to a closed position to cut and remove material engaging over the concave edge of said cutout.

4. A water gate structure comprising an upstanding frame formed of a semi-circular upper portion and a rectangular lower portion, a plate fixed to one side of said rectangular lower portion and formed with a cutout, a rotatable gate for closing the cutout slidably mounted relative to the plate and in vertical alignment therewith, means pivotally securing said gate to said rectangular lower portion, sealing members carried by the gate and slidably engaging the opposite faces of said plate, means for rotating said gate, and means carried by said semi-circular frame portion disposed in vertical alignment with said plate and engageable between said sealing members for guiding said gate during the movement thereof to an open position.

5. A water gate structure comprising an up-

standing frame formed of a semi-circular upper portion and a rectangular lower portion, a plate fixed to one side of said rectangular lower portion and formed with a cutout, a rotatable gate for closing the cutout slidably mounted relative to the plate and in vertical alignment therewith, means pivotally securing said gate to said rectangular lower portion, sealing members carried by the gate and slidably engaging the opposite faces of said plate, means for rotating said gate, means carried by said semi-circular frame portion disposed in vertical alignment with said plate and engageable between said sealing members for guiding said gate during the movement thereof to an open position, and correlated means carried by said gate rotating means and said semi-circular frame portion for receiving a latching means to latch the gate against rotation.

6. A water gate structure comprising an upstanding frame, an upstanding plate within and carried by said frame and formed with a substantially semi-circular cutout opening at the top edge of the plate, a rotatable semi-circular gate engageable in said cutout, means connected to the gate in proximity to its straight edge for rotatably supporting said gate, and means extended laterally from one end of the straight edge of the gate for rotating said gate.

7. A water gate structure comprising an upstanding frame, an upstanding plate within and carried by said frame and formed with a substantially semi-circular cutout opening at the top edge of the plate, a rotatable semi-circular gate engageable in said cutout, means connected to the gate in proximity to its straight edge for rotatably supporting said gate, means extended laterally from one end of the straight edge of the gate for rotating said gate, and said frame and gate having correlating means whereby said gate may be locked against rotation.

8. A water gate structure comprising an upstanding frame, a plate carried by said frame and formed with a substantially semi-circular cutout, a rotatable semi-circular gate engageable in said cutout, means rotatably supporting said gate, means whereby said gate may be locked against rotation, a pair of arcuate strips secured to said gate and overlapping the opposite faces of said plate, and a cleaning blade carried by each strip at one end thereof.

9. A water gate structure comprising an upstanding frame, an upstanding plate within and carried by said frame and formed with a substantially semi-circular cutout opening at the top edge of the plate, a rotatable semi-circular gate operating in said cutout for closing it and carrying means for slidably opposing the faces of said plate bordering said cutout, means rotatably supporting said gate, means for rotating said gate, and the said means carried by said gate provided at one end with means for cleaning the edge of said cutout upon rotation of said gate to a closed position.

10. A water gate structure comprising an upstanding frame formed of a semi-circular upper portion and a rectangular lower portion, a vertical plate supported by said rectangular lower portion and formed with a semi-circular cutout opening at the top edge of the plate, a rotatable gate for closing the cutout having a straight edge and an arcuate edge, said arcuate edge normally opposing and slidably mounted relative to the curved edge of said plate and pivotally con-

nected adjacent to and centrally with respect to said straight edge with said rectangular portion, and means for rotating said gate relative to said frame.

11. A water gate structure comprising an upstanding frame formed of a semi-circular upper portion and an upstanding rectangular lower portion, a plate supported by said rectangular lower portion and formed with a semi-circular cutout opening at the top edge of the plate, a rotatable gate for closing the cutout having a straight edge and an arcuate edge, said straight

edge normally opposing and slidably mounted relative to the curved edge of said plate and pivotally connected adjacent to and centrally with respect to said straight edge with said rectangular portion, sealing members carried by the gate extending from the arcuate edge of the latter and opposing the opposite faces of the plate bordering the curved edge of the cutout, and means for rotating said gate relative to said frame.

10

JOHN WINSTON ALTER.
